CLAIM

The ornamental design for a spray paint screen holder,
as shown and described.

DESCRIPTION

FIG. 1 is a top perspective view of a spray paint screen holder showing my new design;

FIG. 2 is a top plan view thereof;

FIG. 3 is a right side elevational view thereof;

FIG. 4 is a left side elevational view thereof;

FIG. 5 is a bottom plan view thereof;

FIG. 6 is a front elevational view thereof; and

FIG. 7 is a rear elevational view thereof.

The broken line showing of a spray paint screen is for
illustrative purposes only and forms no part of the
claimed design.
